UNITED STATES PATENT OFFICE.

ABRAHAM M. GOLDSMITH, OF NEW YORK, N. Y.

INCINERATOR.

Application filed April 26, 1928. Serial No. 272,899.

The present invention relates to incinerators which are suitable for use in incinerating small quantities of refuse, such as paper, etc. To answer commercial requirements, these incinerators must be of a size suitable to be transported to the user, although they need not be readily portable. Existing designs have usually been unsightly, and the sheet metal construction thereof, as well as the configuration of the incinerator, has necessitated their use in out of the way places where their unattractive character is not a serious objection.

In parks and similar localities it is desirable to have these incinerators located at frequent intervals about the grounds to facilitate the upkeep thereof. An object of this invention is to provide a construction which has a pleasing appearance and harmonizes agreeably with the surrounding conditions. The specific construction embodied herein includes an incinerator shaped in the form of a tree stump. Adjacent the top portion thereof, and at the side, a suitable opening is provided to receive the rubbish to be burned. The top of the incinerator is closed to resemble the top of a sawed-off stump and suitable holes and grate bars are formed in the body of the incinerator. The structure is made as a unit with no removable parts and formed with concrete and reinforcing material.

The invention will be understood more fully in connection with the accompanying drawings, wherein:

Figure 1 is a view in front elevation, partly broken away, showing an incinerator constructed in accordance with the present invention.

Figure 2 is a perspective view of the incinerator shown in Figure 1.

Figure 3 is a plan view, partly broken away, showing the incinerator of Figure 1. Referring to the above drawings, the in-

cinerator is formed in the shape of a tree stump having generally cylindrical sides *a* in which irregularities are cast to resemble the bark of a tree. The lower portion of the sides may flare outwardly as at *a'* and suitable vent holes *b* are provided to facilitate the draft through the incinerator.

Above the vent holes *b* grate bars *c* are provided, these bars being moulded with the body of the incinerator. A large opening *d* is formed in the front of the incinerator, immediately below the top *e*. Through this opening refuse may be deposited within the incinerator preparatory to burning. About the top of the sides *a*, vent holes *f* are formed, being spaced in such a manner that a draft through the top will always be induced, regardless of the weather conditions.

From the above it will be seen that an incinerator of a monolithic character has been provided, the shape of which resembles that of a tree stump. The incinerator may be placed in quite conspicuous surroundings without detracting from the esthetic appearance thereof and by reason of its simplicity of construction as well as its ruggedness of character requires no attention from the standpoint of maintenance. The entire incinerator is formed as a one piece casting and there are no parts to become lost.

I claim as my invention:

A one-piece incinerator comprising side walls and an imperforate top wall formed integral with one another, an opening in the side walls adjacent the top wall, an opening in the side walls adjacent the bottom thereof, and laterally extending grate bars moulded fixedly in the side walls above the upper edge of said bottom opening but adjacent thereto.

This specification signed this 19th day of April, A. D. 1928.

ABRAHAM M. GOLDSMITH.
